CLAIM

The ornamental design for a cover for a curling brush, as shown and described.

DESCRIPTION

FIG. 1 is a perspective view of the cover for a curling brush showing my new design as seen from the top, rear and left side;

FIG. 2 is a left side elevational view thereof, the opposite right side being a mirror image of the side shown;

FIG. 3 is a front elevational view thereof;

FIG. 4 is a rear elevational view thereof;

FIG. 5 is a top elevational view thereof;

FIG. 6 is a bottom elevational view thereof; and,

FIG. 7 is a reduced perspective view thereof, shown exploded from a curling brush which is shown in broken lines for illustrative purposes only and forms no part of the claimed design.
